UNITED STATES PATENT OFFICE.

WALTER KIDDE, OF MONTCLAIR, AND BARZILLAI G. WORTH, OF WEST ORANGE, NEW JERSEY, ASSIGNEES TO WALTER KIDDE & COMPANY, A CORPORATION OF NEW JERSEY.

DETECTION OF SUSPENDED MATTER IN GASES.

Application filed June 28, 1921. Serial No. 480,967.

To all whom it may concern:

Be it known that we, WALTER KIDDE, a citizen of the United States, residing at Montclair, in the county of Essex and State 5 of New Jersey (post-office address No. 56 Gates Avenue, Montclair, N. J.), and BARZILLAI G. WORTH, a citizen of the United States, residing at West Orange, in the county of Essex and State of New Jersey 10 (post-office address No. 422 Gregory Avenue, West Orange, N. J.), have jointly invented certain new and useful Improvements in Detection of Suspended Matter in Gases.

Our invention herein described has for 15 its object the detection and observation of suspended matter in air or other gases. It is particularly applicable to the detection of very minute quantities of smoke in air, but is equally effective in the detection of suspended dust particles, partially condensed vapors and other forms of suspended matter, the detection and observation of which may be desirable in various arts. A 20 specific embodiment of the invention relates to the detection of smoke in apparatus for indicating and extinguishing fires in vessels or buildings, and particularly of the type disclosed in Patent No. 1,343,911, June 22, 25 1920, wherein a pipe leads from each of several compartments of the vessel to an indicating cabinet whereby a fire originating in any compartment will betray its presence by smoke issuing from the mouth 30 of the corresponding pipe in the indicating cabinet, and can thereupon be extinguished by directing a fire extinguishing gas or vapor through said pipe. It is obvious that the detection of a fire should be made as 35 40 speedily as possible after its inception, and it is therefore important that the presence of smoke in the indicating cabinet should be observed even when it exists in very minute quantities. To permit a fire to 45 smolder until relatively large amounts of smoke are produced obviously increases the time required to extinguish the same. By our present invention we are able to detect with entire certainty the presence of smoke 50 55 many times less in amount than could be possibly observed by its issuance into a generally light cabinet from the mouths of the detector pipes as disclosed in our patent above referred to.

Broadly stated our invention consists in

leading the smoke, vapor or other finely suspended matter into a chamber from which general illumination is excluded and utilizing a light beam so directed as to be substantially invisible, the finely suspended 60 matter being caused to progress through the beam whereby the particles will become illuminated by reflection, and their presence thus manifested. Our invention as thus broadly defined may be carried out in many 65 different ways, some of which are illustrated in the accompanying drawings forming part of this specification and to which attention is now directed.

In the drawings:

Fig. 1 shows more or less diagrammatically the constituent parts of a fire indicating and extinguishing system of the type disclosed in our patent referred to, illustrating a convenient arrangement for detecting the 75 presence of smoke issuing from any of the detector pipes.

Fig. 2, an enlarged view partly in section of the detecting device shown in Fig. 1.

Fig. 3, a diagrammatic view illustrating 80 the possibility of using two sources of illumination with a large number of detector pipes.

Fig. 4, a modification showing a single source of illumination with a plurality of 85 detector pipes, the smoke passing transversely through the light beam.

Fig. 5, shows an alternative arrangement in which the light beam is projected downward into a tube; and

Fig. 6, an alternative form of observation tube in which the observation is effected through the transparent wall of a continuous tube.

In all of the above views corresponding 95 parts are represented by the same numerals.

In apparatus heretofore used for detecting smoke or other suspended matter issuing from an orifice, it has been usual to observe the issuing jet by simple unaided vision, the smoke being seen in the general illumination of daylight or other diffused general illumination. This is effective when the smoke or suspended matter is sufficiently dense, but its sensitivity is limited. We 100 have found that greatly improved results may be obtained and the visibility of smoke or other suspended matter may be enormously increased by projecting an intense beam of light through the gas or vapor 110

from a concealed source and observing the illuminated particles from a direction oblique to that of the beam. When the gas or vapor is free from suspended matter, 5 the light and the gas or vapor are invisible, but if suspended matter exists even in minute quantities the particles cause diffraction or reflection of the light which thus becomes visible as a continuous and prolonged beam. In the preferred form of the apparatus where the light is projected through the tube from which the particle-bearing gas or vapor issues, from a source or mirror in the axis of the tube, the 10 slightest trace of suspended matter will cause an appearance as of a glowing coal in the mouth of the tube, with a shaft of light projecting from it. This not only increases enormously the detecting sensitivity 15 of the apparatus, but produces a visual effect so striking as to arrest attention at once, being thus highly efficient as a fire alarm. By means of this invention, smoke or other suspended matter is rendered clearly visible when so highly attenuated that 20 it cannot be detected by ordinary observation.

Referring first to Fig. 1, a pipe 1 is shown leading from the valve cabinet 2 to a compartment 3, the end of the pipe being provided with a hood 4 located preferably near the top of the compartment. It will be understood of course that as many of these pipes 1 are employed as may be needed to 30 reach the several compartments of the ship or other structure with which the apparatus is used. Each pipe is provided with a valve 5 which may be opened to permit steam or other extinguishing medium to 35 pass from the header 6 to which the steam pipe 7 leads, with main valve 8 therein. If desired, carbon-dioxide or other fire extinguishing gas may be admitted to the header 6 from the gas tank 9 through valves 40 10, 10.

Leading from each of the extinguishing pipes 1 is a detector or smoke pipe 11, all of which detector pipes lead to an indicator cabinet 12 having a transparent front 50 13. Each detector pipe is provided with a valve 14 which is normally opened, and each valve is provided with a lever 15 extending down over the hand-wheel of the corresponding steam valve, so that before the 55 steam valve can be opened the corresponding smoke valve 14 must be first closed to prevent steam from entering the detector pipe. This special arrangement of interlocking valves is not claimed herein, but 60 is made the subject of a separate application Serial No. 480,966 filed by us on even date herewith. Suction within the detector pipes is created by a fan 16 as shown, whereby a circulation will be maintained 65 from the several compartments, and any

smoke developed therein will be speedily drawn into the indicator cabinet. In the preferred form of apparatus shown in Figs. 1 and 2, we employ an observation tube or orifice 17 for each detector pipe 11, the latter entering the observation tube preferably at an angle as shown, and the observation tube being located in the bottom of the indicator cabinet whereby the gas or vapor with its suspended matter will be drawn out through the mouth of the observation tube. Coaxial with the observation tube 17 is a source of light 18 which may be an incandescent lamp located directly in the axis as shown in Fig. 6, or a mirror or prism 19 in the axis as shown in Figs. 1 and 2.

In Fig. 2, we show observation tube No. 2 as receiving light directly from the lamp 18, and the other tubes equipped with mirrors so that the light from the same lamp is reflected axially through the tube. Light is thus caused to pass through the tube in the same direction as the current of gas or vapor, forming a beam in which the suspended matter is strongly illuminated. As an alternative the light may be projected in a direction opposite to the gas flow as in Fig. 5. Preferably the beam is concentrated by a lens 20 or equivalent means.

The orifice or observing portion of the tube is so located that the observer views it from a position out of the path of the beam or beams, that is, from an angle oblique to the beam or beams, as indicated in Fig. 1, so that the light is completely invisible when the gas is clear and clean, but any suspended matter acts as a secondary source of light and appears as an illuminated shaft of striking visibility.

In the simple arrangement of Fig. 2 the source of light 18 is shown as an incandescent lamp. The lens 20 is shown as a convex lens mounted in the axis of the observation tube 17 or in an offset, and projecting a concentrated beam of light through the orifice or mouth of the tube. We prefer to employ a lens having a relatively large aperture with relation to its focal length so as to utilize as large a cone of light as possible from the lamp 18, and the distance of the lamp from the lens is preferably so chosen as to focus an image of the filament at a point a short distance above the orifice of the observation tube as indicated in Figs. 2, 5 and 6, the point of focus being shown in direct line with the observer's eye when placed at a convenient point out of the path of the beam. This arrangement results in a highly effective illumination.

Instead of projecting the beam of light on the gas or vapor issuing from the orifice from a point within the orifice, the process may be reversed, a light beam being projected toward the tube from the outside as

- shown in Fig. 5. The source of light 18 is shown projecting a beam through a convex lens 20 to a focal point located a short distance from the orifice of the indicator tube 17. In this case the entire tube constitutes the gas or vapor channel, the branch 11 being omitted, and the light entering the tube from the source above is absorbed without producing a glare visible to the observer.
- 10 For the sake of simplicity of construction, we prefer to locate the tubes approximately in a circle or circles with the source of light at the center. This arrangement has the advantage of permitting the optical 15 systems of all the tubes in a given circle to be made identical or substantially so. Such an arrangement of tubes is shown in plan view in Fig. 3 where two sources of illumination X X serve to illuminate a large 20 number of observation tubes arranged around the source of illumination in substantially concentric circles. To prevent the cutting off of the light from the tubes in the outer circles the tubes may be arranged 25 either between those in the inner circle or in different vertical planes, as shown in Fig. 2, the angle of the mirrors being properly selected to project the light beam axially through the observation tube.
- 30 We prefer to employ a clear glass window 21 at the lower opening of the observation tubes, as shown in Fig. 2 (see tubes Nos. 2 and 3, Fig. 2), in order to protect the optical surfaces of the lens 20 and mirror 19 from dust. Instead of this arrangement the lens itself may be located at this point (see tube No. 1, Fig. 2), in which case the clear glass takes the place of the lens above the mirror. Thus all optical surfaces are protected except those that are readily accessible 40 for cleaning. Each observation tube is made of two sections, as shown in Fig. 2, telescoping together as with common optical instruments and clamped in position by a grip 45 ring 22, thus permitting both vertical and angular adjustment and allowing also the lower section of any tube to be removed for the purpose of cleaning the same.
- 50 While we prefer to employ an observation tube terminating in an open mouth or orifice as described, this is not necessary and sometimes, as in the case of noxious gases, not desirable. For example the tube may be continuous and its observation portion 55 made of glass or other transparent material, as in Fig. 6. In this case care should be taken to prevent the beam of light from striking the glass and thus producing a visible illumination. This may be done by 60 restricting the diameter of the tube at the point 24, as shown.
- 65 Another alternative arrangement is shown in Fig. 4. Here the light beam is not axial with the tube, as in the preferred form, but is projected horizontally above a row of observation tubes, finally passing into a blackened chamber 25 where it is absorbed without being visible to the observer unless it impinges upon suspended matter issuing from the orifice of one of the observation 70 tubes. With this modification of the invention, two plano-convex lens 27 are employed to form a parallel light beam which projects across the mouths of the observation tube.
- 75 The operation of the device has been already generally indicated. Normally the steam valves 5 are closed and the valves 14 opened so that the suction fan 16 will cause a circulation of air from within all the compartments or rooms of a ship or building or other structure to be protected. Preferably a perforated plate 28 is mounted near the top of the observation cabinet 12, so as to secure a uniform suction over the whole area of this cabinet, whereby the smoke issuing from the orifice of the observation tubes will be drawn directly upward following the path of the light beams and not deflected by eddies. Obviously any other form of exhaust which produces a substantially uniform flow of air or gas may be employed. A canopy or screen 29 prevents the observer from seeing the upper blackened portion of the indicator cabinet in which the light is absorbed without producing a distracting glare. In case fire occurs in any of the compartments, its presence will be indicated by smoke passing up through the detector pipe and through the corresponding observation tube. By reason of the illuminating device described, this smoke even when extremely attenuated will be readily and strikingly indicated. The observer, noting the orifice from which the smoke passes and thus locating the compartment in which fire has occurred, will thereupon proceed to close the valve 14 of the corresponding detector pipe and open the steam valve 5 thereof, whereby steam will be allowed to enter the compartment and thus extinguish the fire. When the valve cabinet 2 is located at a distance from the detector cabinet, for instance, at or near the engine room, the proper instructions as to 100 location of the fire will be given by telephone 105 or otherwise.
- 110 It will be readily understood that the means for observing suspended matter here set forth is applicable not only to the detection of smoke, but it may be used also for a variety of other purposes. Among the possible applications of the invention may be mentioned the observation of flue gases from furnaces for detecting suspended solid matter due to incomplete composition, the 115 detecting of dust in air, in mines, factories, coal grinding establishments, flour mills, etc., the observation of steam, fog, or partially condensed vapor.
- 120 Having now described our invention, what 125

we claim as new therein and desire to secure by Letters Patent is as follows:

1. The method of observing suspended matter in a gas or vapor, which consists in causing a stream of gas or vapor to flow into the path of a light beam normally invisible to the observer, and observing the illuminated suspended matter from a point out of the path of the light beam, substantially as set forth. 70
2. The method of observing suspended matter in a gas or vapor, which consists in causing a restricted stream of gas or vapor to flow in contact with a light beam normally invisible to the observer, and observing the illuminated suspended matter from a point out of the path of the light beam. 75
3. The method of observing suspended matter in a gas or vapor which consists in causing a stream of gas to flow through a tube, illuminating the gas or vapor stream by a light beam normally invisible to the observer, and observing the illuminated suspended matter from a point out of the path 80 of the light beam, substantially as set forth. 85
4. The method of observing suspended matter in a gas or vapor, which consists in causing a stream of gas or vapor to flow parallel with a light beam and observing the illuminated suspended matter from a point out of the path of the beam, substantially as set forth. 90
5. The method of observing suspended matter in a gas or vapor, which consists in causing a stream of gas or vapor to flow parallel with a light beam normally invisible to the observer, and observing the stream from a point where it becomes visible by diffraction or reflection when suspended matter is present, substantially as set forth. 95
6. The method of observing suspended matter in a gas or vapor, which consists in causing a stream of gas or vapor to flow through a tube, illuminating the gas stream by a light beam also traversing the tube and observing the illuminated suspended matter from a point out of the path of the beam, substantially as set forth. 100
7. The method of observing suspended matter in a gas or vapor which consists in causing the gas or vapor with its suspended matter to issue from an orifice, projecting a beam of light in line with the stream of gas and observing the illuminated matter from a point out of the path of the beam. 110
8. The method of observing suspended matter in a gas or vapor, which consists in causing the gas with its suspended matter to issue from an orifice, projecting a beam of light through the orifice on the matter issuing thereon, and observing the illuminated matter from a point out of the path of the beam, substantially as set forth. 115
9. The method of observing suspended matter in a gas or vapor which consists in causing the gas or vapor with its suspended matter to issue from an orifice, projecting a beam of light through the orifice in an axial direction, and observing the illuminated suspended matter from an angle oblique to the axis, substantially as set forth. 120
10. The method of observing suspended solid matter in a gas or vapor, which consists in causing the gas or vapor with its suspended matter to pass through a tube, projecting a concentrated axial beam of light through the tube from a source external to the tube, and observing the illuminated matter from an angle oblique to the axis, substantially as set forth. 125
11. The method of observing suspended solid matter in a gas or vapor, which consists in causing the gas and suspended matter to issue from an orifice, projecting through the orifice a beam of light normally invisible to the observer, but becoming visible by diffraction or reflection when suspended solid matter is present, substantially as set forth. 130
12. Apparatus for detecting suspended matter in gases, in which are combined an observation tube, means for causing a current of gas with suspended matter to flow through the tube, means for projecting a beam of light through the tube parallel with its axis, and means for observing the illuminated suspended matter from an angle oblique to the axis, substantially as set forth. 135
13. An apparatus for detecting suspended matter in gases, in which are combined an observation orifice, means for passing a current of gas or vapor with its suspended matter through the orifice, a source of light, means for projecting a concentrated beam from said source through the gas or vapor current, and means for observing the illuminated suspended matter from a point out of the path of the beam, substantially as set forth. 140
14. An apparatus for detecting suspended matter in gases or vapors, in which are combined an observation orifice, means for passing a current of gas or vapor with its suspended matter through the orifice, a source of light, means for projecting a concentrated beam from said source axially with respect to the gas or vapor current, and means for observing the illuminated suspended matter from a point out of the path of the beam. 145
15. An apparatus for detecting suspended matter in gases or vapors, in which are combined an observation orifice, means for passing a current of gas or vapor with its suspended matter through the orifice, a source of light, means for projecting a concentrated beam from said source through said orifice, and means for observing the illuminated suspended matter from a point out of the beam. 150

the path of the beam, substantially as set forth.

16. An apparatus for detecting suspended matter in gases or vapors, in which are combined an observation orifice, means for causing a current of gas or vapor with suspended matter to issue from said orifice, a source of light located out of the axis of the orifice, and a mirror located in said axis and projecting an axial beam from said source through the orifice, substantially as set forth. 70

17. An apparatus for detecting suspended matter in gases or vapors, in which are combined an observation orifice, means for causing a current of gas or vapor with suspended matter to issue from said orifice, a source of light located out of the axis of the orifice, a mirror located in said axis and projecting an axial beam from said source through the orifice, and a lens for concentrating said beam, substantially as set forth. 80

18. An apparatus for detecting suspended matter in gases or vapors, in which are combined a plurality of observation orifices, means for passing currents of gas or vapor with its suspended matter through said orifices, a single source of light, means for projecting a concentrated beam from said source with respect to the several orifices and in contact with the several gas or vapor currents, and means for observing the illuminated suspended matter from a point out of the path of the several beams, substantially as set forth. 90

19. An apparatus for detecting suspended matter in gases, in which are combined a plurality of observation orifices, means for passing currents of gas or vapor with its suspended matter through said orifices, a single source of light, means for projecting a concentrated beam from said source axially with respect to the several gas or vapor currents, and means for observing the illuminated suspended matter from a point out of the path of the beam, substantially as set forth. 100

20. An apparatus for detecting suspended matter in gases, in which are combined a plurality of observation orifices, means for passing a current of gas or vapor with its suspended matter through the several orifices, a source of light, means for projecting a concentrated beam from said source through each of the several orifices, and means for observing the illuminated suspended matter from a point out of the paths of the beams, substantially as set forth. 110

21. An apparatus for detecting suspended matter, in which are combined a plurality of observation orifices arranged substantially circularly, a single source of light located centrally with respect to the several orifices, means for passing a current of gas or vapor with its suspended matter through the sev-

eral orifices, means for projecting a concentrated beam from a single source axially with respect to the several gas or vapor currents, and means for observing the illuminated suspended matter from a point out of the paths of the beams, substantially as set forth. 75

22. An apparatus for detecting suspended matter in gases or vapors in which are combined a plurality of observation orifices arranged substantially circularly, a source of light centrally located with respect to said orifices, means for passing a current of gas or vapor with its suspended matter through each of said orifices, means for projecting a concentrated beam from the single source through each orifice, and means for observing the illuminated suspended matter from a point out of the path of the beam, substantially as set forth. 85

23. An apparatus for detecting suspended matter in gases, in which are combined a plurality of observation orifices arranged approximately in concentric circles, a single source of light centrally located with respect to said orifices, means for passing a current of gas or vapor with its suspended matter through the several orifices, means for projecting a concentrated beam from said source axially with respect to the several orifices, and means for observing the illuminated suspended matter from a point out of the paths of the beams, substantially as set forth. 95

24. An apparatus for detecting suspended matter in gases or vapors, in which are combined a plurality of observation orifices located approximately in concentric circles, a single source of light centrally located with respect to said orifices, means for passing a current of gas with its suspended matter through the several orifices, means for projecting a concentrated beam from the single source through the several orifices, and means for observing the illuminated suspended matter from a point out of the paths of the beams, substantially as set forth. 100

25. An apparatus for detecting suspended matter in gases, comprising in combination an observation cabinet, means for exhausting air therefrom, a plurality of observation orifices opening into said cabinet, connections for admitting gas or vapor with suspended matter to said orifices whereby currents of gas or vapor will flow therefrom, means for projecting light in contact with the gas or vapor currents, and means for observing the illuminated suspended matter from an angle oblique to the axis, substantially as set forth. 115

26. An apparatus for detecting suspended matter in gases, comprising in combination an observation cabinet, means for exhausting air therefrom, a plurality of observation orifices leading into the cabinet, connections 120

for admitting gas or vapor with its suspended matter into each orifice whereby a current of gas or vapor will flow therefrom, means for projecting a concentrated light beam axially with respect to each orifice, and means for observing the illuminated suspended matter from a point out of the paths of the beams, substantially as set forth.

27. An apparatus for detecting suspended matter in gases, comprising in combination an observation chamber, means for exhausting air therefrom, a plurality of observation orifices leading into said chamber, means for admitting gas or vapor with its suspended matter to each orifice, whereby a current of gas or vapor will issue therefrom, means for projecting a concentrated light beam through each orifice, and means for observing the illuminated suspended matter from a point out of the paths of the beams, substantially as set forth.

28. An apparatus for detecting suspended matter in gases, comprising in combination an observation cabinet, means for exhausting air therefrom, connections for admitting gas or vapor with its suspended matter to each orifice, whereby currents of gas or vapor will issue therefrom, a single source

of light, means for projecting a concentrated beam from said source axially with respect to the several orifices, and means for observing the illuminated suspended matter from a point out of the paths of the beams, substantially as set forth.

29. An apparatus for detecting suspended matter in gases, comprising in combination an observation cabinet, means for exhausting air therefrom, a plurality of observation orifices leading into said cabinet, connections for admitting gas or vapor with its suspended matter to said orifices, whereby currents of gas or vapor will issue therefrom, a single source of light, means for projecting a concentrated beam from said source, through each of the several orifices, and means for observing the illuminated suspended matter from a point out of the paths of the beams, substantially as set forth.

This specification signed and witnessed this 24 day of June, 1921.
